(57) **CLAIM**

The ornamental design for a positioning grip for a mobile electronic device, as shown and described.

DESCRIPTION

FIG. 1 is a perspective view of a the positioning grip for a mobile electronic device showing the new design;

FIG. 2 is a front elevation view thereof;

FIG. 3 is a left elevation view thereof;

FIG. 4 is a rear elevation view thereof;

FIG. 5 is a right elevation view thereof;

FIG. 6 is a top plan view thereof;

FIG. 7 is a bottom plan view thereof; and,

FIG. 8 is a perspective view of the positioning grip for a mobile electronic device showing a second position of use. The broken lines are for the purpose of illustrating environment and forms no part of the claimed design.
